UNITED STATES PATENT OFFICE.

WARREN V. JOHNSON, OF BLOOMSBURG, PENNSYLVANIA, ASSIGNOR TO AMERICAN CAR AND FOUNDRY COMPANY, OF NEW YORK, N. Y., A CORPORATION OF NEW JERSEY.

MINE CAR.

Application filed August 8, 1923. Serial No. 656,372.

To all whom it may concern:

Be it known that I, WARREN V. JOHNSON, residing at Bloomsburg, Columbia County, State of Pennsylvania, and being a citizen 5 of the United States, have invented certain new and useful Improvements in a Mine Car, of which the following is a full, clear, and exact description, such as will enable others skilled in the art to which it apper- 10 tains to make and to use the same, reference being had to the accompanying drawings, which illustrate the preferred form of the invention, though it is to be understood that the invention is not limited to the exact de- 15 tails of construction shown and described, as it is obvious that various modifications thereof within the scope of the claims will occur to persons skilled in the art.

In said drawings:

20 Figure 1 is a plan view of an improved mine car with a portion of the floor broken away to show the underframe and draft mechanism assembly;

25 Figure 2 is a view of the car side showing the steel frame superstructure;

30 Figure 3 is an end elevational view of the fixed end of the car with a corner thereof broken away to show a section through the floor, underframe and side wall super- structure;

35 Figure 4 is an end elevational view of the gate end of the car showing the method of mounting the gate bearings on the side wall superstructure; and

40 Figure 5 is a modified side wall super- structure involving the use of a bottom en- gaging angle strip.

45 My invention relates to mine and other industrial cars having wood underframing and steel frame superstructure, and has for one of its objects the elimination of the transverse body bands heretofore used to brace the body of the car and for the support of the flooring.

50 A further object is to provide a draft mechanism which utilizes, in the final stages of its movement, the longitudinal tie rods connecting the underframe members and providing the necessary support for the moving parts of said mechanism.

55 In said drawings, 10 is the wooden under- frame comprising the longitudinal side sill members 11, the end sill members 12, and other cross members 13 intermediate the end sills 12. The end sills 12 are preferably of

less depth than the side sills 11 but are connected to them with their upper faces relatively flush to provide a flat support for the flooring 23. The side sills 11 have their ends abutting the inner faces of the end sills 12 and are preferably connected to the end sills at points inside of the plane of the end sill ends as best shown in Figures 1 and 3. The side and end sills are connected by inside connection pieces 14, said connection pieces being secured by a suitable number of bolts 17 and 18 disposed horizontally in the side and end sills respectively. Suitable pockets 20 may be secured to the inner faces of the side sills 11 by bolts 19 to provide 60 seats for the transverse intermediate members 13, and deriving a portion of their support from respectively adjacent tie rods 21 tying the side sills together and passing 65 through said pockets as best shown in Figure 1. The underframe members are further connected longitudinally by the draft rods 50 more fully hereinafter referred to. Mounted upon the underframe is the super- 70 structure framed in steel and comprising 75 preferably a steel floor portion 23 having the marginal side flanges 24 secured to the lower ends of a plurality of upright fram- 80 ing members 25 and 26 forming respectively 85 the intermediate and corner post elements 90 of the side wall structure. At their upper 95 ends said posts are connected by means of the side wall protection strip 27 forming the top chord element of the side wall fram- 100 ing. Diagonal braces 28 connect the strip 27 and floor flange 24 at points between the 105 respectively adjacent intermediate and corner post members 25 and 26. Thus assem- bled, with the floor flanges forming the lower chord element of the truss structure, a rigid side wall framing is provided to which may be applied the usual wall boards 30 removably secured to the framing by bolts 31 and overlying the flooring. In- stead of utilizing a lower chord element 100 forming an integral part of the car floor, a chord member of commercial rolled shape such as the angle 32 could be substituted and separate flooring 33 assembled there- 105 with as shown in Figure 5.

In both embodiments of the side wall structure the wall boards 30 are held rigidly in position with the upper edge of the top wall board housed within the substan- 110 tially channel shaped top chord 27. Thus

positioned, the wall boards and framing members when secured together will mutually reinforce each other to prevent outward bulging of the side wall structure and carry 5 a large percentage of the load.

The fixed end wall 35 of the car may be similarly assembled with intermediate end posts 36 and corner posts 26. The corner posts 26 are preferably common to the end 10 wall 35 and the side wall structures as shown in the drawings but may be separate members if desired. The end wall top and bottom chords may form part of similar members in the side wall structures, but it may 15 be found expedient to form said members separately.

At the gate end of the car the side walls are tied together by means of a rod 37 held in brackets 38 mounted at the adjacent ends 20 of the side walls and prevented from shifting longitudinally by cotters 39, or the like, passing through said rod immediately adjacent the outer sides of the brackets 38. The rod serves as a pintle for the hinges 40 of 25 the swinging gate 41, and the gate is kept clear of the side walls by the spacing thimbles 42 sleeved on the rod between abutments formed by the inner sides of rod brackets 38 and outer sides of the hinges 40. The gate 30 is locked by the bar latches 44 pivoted on the gate at 45 and having their free ends engaging the keepers 46 on the car.

The draft mechanism for the car comprises a pair of longitudinal tie rods 50 extending 35 through the end sills 12 and fitted at their ends with securing nuts 51 having a bearing against wear plates 52 secured to the outer faces of the end sills. Drawbars 53 extend inwardly through the end sills 12 and are 40 mounted at their inner ends for yielding movement under draft strains. Such mounting comprises the transversely extending follower bars 54 to which the drawbars are pivotally secured by pins 55. The followers 45 ride upon the tie rods 50 as best shown in Figures 1 and 2 and are movable with the drawbars 53. Suitable draft springs 56 are mounted on the drawbars between their respective followers and end sills providing 50 abutments for the ends of the springs. Also mounted upon the tie rods 50 between the ends of the followers 54 and their respective end sills are spacing sleeves 57 designed to prevent abnormal compression of the springs 55 56 under exceptional draft strains and to distribute the stresses of draft over a larger area on the respective end sill members 12, thence through the tie rods to the opposite end sill member.

60 To protect the protruding drawbar heads from damage upon impact with other cars, buffer blocks 60 are secured to each end sill on opposite sides of the drawbar and preferably in line with the side sill members 11 65 of the underframe. They may be secured

as shown in the drawings by bolts 61 taking one flange of the outside connection piece 15 connecting the side and end sills, the other flange of the connection taking bolts 17 securing inside connections 14 to the side sills. 70 The drawhead sides of the buffers are secured by bolts 62 taking the end sill and draft reinforcement plate 63 on the inner face of the end sill.

From the foregoing it will be noted that 75 the reinforcement plate 63 acts not only as a wearing piece for the spring 56 and spacing sleeves 57 but serves also to connect the buffer blocks 60 and the side sills 11 together and to the end sill. It will also be noted 80 that the car body rests upon the end sills, the intermediate cross members 13, and the side sills 11, and extends outwardly beyond the side sills, the body deriving its support in the plane of its side walls from the side 85 wall framing trusses supported at their ends upon the end sills to which they are secured. The flooring is secured to the underframe members in any suitable manner, preferably by bolts 59 as best shown in Figures 3 90 and 5.

Constructed as described the car is well adapted to withstand the rough usage of mining service, is ruggedly and economically 95 assembled, and easily repaired. The completed body is mounted upon any approved running gear shown in broken lines in Figures 1 and 2 of the drawings and designated in its entirety by the reference numeral 9.

What I claim is:

1. A car structure comprising an underframe having side and end sills, a flooring mounted upon said sills and extending outwardly beyond the side sills, side walls secured to said flooring and at one end of the car resting upon an end sill, an end wall connected with the side walls and supported by the end sill at the said end of the car, a gate at the opposite end of the car, and mounting means for the gate connected with the side walls and retaining the side walls in predetermined spaced relation. 100

2. A car structure comprising an underframe having side and end sills, a flooring mounted upon said sills and extending outwardly beyond the side sills, side walls extending upwardly from said flooring and having their ends resting upon said end sills, an end wall disposed above one end sill and connected with said side walls, an end gate at the opposite end of said side walls, and a mounting rod for said gate connected with the last mentioned end portions of said side walls and serving as a tie rod 110 for the side walls.

3. A car having an underframe having side and end sills and a metal frame superstructure having side and end walls, the side walls of said framing structure being positioned outside the plane of said side walls 120 125 130

and comprising top and bottom chord members and connecting upright members, and a flooring mounted on said underframe and extending beyond said side sills and having 5 said bottom chord members connected therewith.

4. A car having an underframe including side and end sills and a metal frame superstructure having side walls comprising top 10 and bottom chord members and connecting uprights positioned in a plane outside of the side sills and supported at their ends upon the end sills, and a flooring mounted upon said underframe and connecting said bottom chord members and uprights of the framing.

5. A car having an underframe including side and end sills and a metal frame superstructure having side walls comprising top 20 and bottom chord members and connecting upright members positioned in a plane outside of the side sills and supported at their ends upon the end sills, a plurality of wall boards secured to said side wall framing 25 members, and a flooring underlying said wall boards and connecting said bottom chord members and uprights of the framing.

6. A car structure comprising an underframe having side and end sills, a flooring mounted upon said sills and extending outwardly beyond the side sills, side walls extending upwardly from said flooring along the sides thereof and having their 35 ends resting upon said end sills, an end wall connected with the side walls at one end of the car structure and disposed above an end sill, and an end gate connected with the other end portions of said side walls.

40 7. A car underframe comprising connected side and end sills, longitudinally extend-

ing tie rods disposed between the side sills in spaced relation to each other and having their end portions carried by said end sills, 45 drawbars slidable through said end sills and extending inwardly between the tie rods and connected with the inner ends of said drawbars, and resilient means between the cross heads and end sills for yieldably holding the drawbars against outward movement. 50

8. A car underframe comprising connected side and end sills, longitudinally extending tie rods disposed between the side sills in spaced relation to each other and having their end portions carried by said end sills, 55 drawbars extending longitudinally between the tie rods and disposed inwardly and outwardly of the end sills, cross head slidably carried by said tie rods and pivotally connected with the inner ends of said drawbars to mount the drawbars for longitudinal 60 sliding movement and transverse swinging movement, springs upon the drawbars between the cross heads and end sills to resist outward movement of the drawbars, and means upon the tie rods between the cross heads and end sills for limiting outward movement of the drawbars. 65

9. In a car underframe comprising side and end sills, transverse and longitudinal 70 tie rods respectively connecting said sills, draft mechanism yieldingly mounted on the longitudinal rods adjacent the end sills, and a wear and tie plate on the inner face of the respective end sills in position to engage said draft mechanism, said plate being adapted to connect said side sills together and to the respective end sill. 75

In witness whereof I have hereunto set my hand.

WARREN V. JOHNSON.
